US0D1069945S

(12) **United States Design Patent** (10) **Patent No.:** **US D1,069,945 S**
(45) **Date of Patent:** **** Apr. 8, 2025**

(54) **TRAINING DEVICE**

(71) Applicant: **Besil Özkaya**, Worms (DE)

(72) Inventor: **Besil Özkaya**, Worms (DE)

(**) Term: **15 Years**

(21) Appl. No.: **29/861,262**

(22) Filed: **Nov. 29, 2022**

(51) **LOC (15) Cl.** **21-02**

(52) **U.S. Cl.**

USPC **D21/691**; D21/662; D21/673; D21/679;
D21/698

(57) **CLAIM**

The ornamental design for a training device, as shown and described.

DESCRIPTION

FIG. 1 is a front right perspective view of a training device showing my new design;

FIG. 2 is a left side view thereof;

FIG. 3 is a right side view thereof;

FIG. 4 is a top view thereof;

FIG. 5 is a bottom view thereof; and,

FIG. 6 is a rear view thereof.

The broken lines shown in the drawings show portions of the training device and form no part of the claimed design. The paired zig-zag lines show bounds of the claimed design and form no part of the claimed design. The area between the lines forms no part of the claimed design.

1 Claim, 6 Drawing Sheets
